US0D1006760S

(12) **United States Design Patent** (10) Patent No.: **US D1,006,760 S**
(45) Date of Patent: ** Dec. 5, 2023

(54) **PLUG**

(71) Applicant: **Deals Realm LLC**, Eastvale, CA (US)

(72) Inventor: **Yuebo Tao**, Guangdong (CN)

(73) Assignee: **Deals Realm LLC**, Eastvale, CA (US)

(**) Term: **15 Years**

(21) Appl. No.: **29/889,584**

(22) Filed: **Apr. 13, 2023**

(30) **Foreign Application Priority Data**

Nov. 8, 2022 (CN) 202230743873.7

(51) **LOC (14) Cl.** **13-03**

(52) **U.S. Cl.**

USPC **D13/138.2**

(58) **Field of Classification Search**

USPC D13/138.1-138.2, 137.1-137.2, 139.7,
D13/199

See application file for complete search history.
